UNITED STATES PATENT OFFICE.

HENRY S. REYNOLDS, OF BROOKLYN, ASSIGNOR TO THE IRON CLAD MANUFACTURING COMPANY, OF NEW YORK, N. Y.

WATERING-POT.

SPECIFICATION forming part of Letters Patent No. 236,359, dated January 4, 1881.

Application filed August 24, 1880. (No model.)

To all whom it may concern:

Be it known that I, HENRY S. REYNOLDS, of Brooklyn, in the county of Kings and State of New York, have invented certain new and useful Improvements in Watering-Pots, of which the following specification is a description.

This invention consists in making the cylinder and spout of a watering-pot of the same pieces of metal by forming them of two pieces of metal stamped up to the requisite shape. Heretofore such cylinders were made of a straight piece of metal, worked up in the shape of a cylinder, and having its edges soldered together at the center. A hole was then made in the front part of the cylinder near the bottom to connect with the spout, which was soldered to the cylinder at this opening. The result of this construction was that the watering-pot would be liable to leak at the point where the spout was soldered to it.

The object of this invention is to obviate this difficulty by making the spout of the same pieces of metal as the cylinder, and thereby absolutely preventing leakage at this point.

In the accompanying drawings, Figure 1 is a side view of a watering-pot the cylinder and spout of which are made according to my improvement. Fig. 2 is a transverse section thereof, taken on the plane of the line xx , Fig. 1. Fig. 3 is a vertical section taken on the plane of the line yy , Fig. 1; and Fig. 4 is a transverse section taken on the plane of the line zz , Fig. 1.

Similar letters of reference indicate corresponding parts in all the figures.

In the drawings, A designates the cylinder of a watering-pot, and B the spout formed of two pieces of metal stamped up to the requisite shape. The edges are grooved, so as to fit snugly together and make a tight joint front and rear.

C designates the bottom and D the breast. These parts are fastened to the cylinder in the same manner as the edges of the cylinder are joined together, although any other suitable means may be employed.

H and H' designate the handles, which are riveted or otherwise secured to the pot.

n designates the nozzle, which fits over the end of the spout and is fastened thereto. This nozzle n supports the rose-holder, which is soldered or otherwise fastened to its end, and

the rose screws onto this rose-holder, and is detachable therefrom. The rose and rose-holder are not shown in the drawings; but it is intended to use such devices of the ordinary construction.

In practice I take two pieces of metal of the proper size, stamp them up to form the cylinder and spout, and then unite the edges by grooving them together. This construction forms a brace, b, between the spout and cylinder, and the edges of this brace are overlapped by a metal strip, which is fastened thereto by riveting right through it and the brace. The bottom C and breast D are then fastened to the cylinder by grooving, and the handles H H' and nozzle n are attached, all as above described. The whole structure is then galvanized, and the material used in this process fills in around the seams and makes them perfectly water-tight.

The advantages of this construction of a watering-pot over those heretofore in use are that its manufacture involves considerable less labor, thereby lessening the first cost. The spout is part of the cylinder and cannot be knocked off in use, nor will there be any danger of leakage. In the old style of pots the spout would frequently become detached from the cylinder while in use, or be bent, thereby weakening the joint between it and the cylinder and causing leakage. Besides this, this joint would very often be imperfectly made and the pot would leak at this point.

What I claim as my invention, and desire to secure by Letters Patent, is—

1. In a watering-pot, the combined cylinder and spout made of two pieces of metal, stamped up to the requisite shape and joined together by grooving, substantially as herein shown and specified.

2. The combination of the combined cylinder and spout A B with the bottom C, breast D, handles H H', and nozzle n, substantially as set forth, for the purposes specified.

3. The combination of the cylinder A, spout B, and brace b with the bottom C, breast D, handles H H', and nozzle n, substantially as set forth, for the purposes specified.

HENRY S. REYNOLDS.
